US0D1028582S

(12) **United States Design Patent** (10) **Patent No.:** **US D1,028,582 S**
(45) **Date of Patent:** **** May 28, 2024**

(54) **STAND FOR DISPLAYING AUGMENTED REALITY GLASSES**

(71) Applicant: **Falcon Innovations Technology (Shenzhen) Co., Ltd**, Shenzhen (CN)

(72) Inventors: **Mingjie Wang**, Shenzhen (CN); **Bin Zheng**, Shenzhen (CN)

(73) Assignee: **Falcon Innovations Technology (Shenzhen) Co., Ltd**, Shenzhen (CN)

(**) Term: **15 Years**

(21) Appl. No.: **35/516,548**

(22) Filed: **Dec. 2, 2022**

(80) **Hague Agreement Data**

Int. Filing Date: **Dec. 2, 2022**

Int. Reg. No.: **DM/227201**

Int. Reg. Date: **Dec. 2, 2022**

Int. Reg. Pub. Date: **Mar. 10, 2023**

(30) **Foreign Application Priority Data**

Oct. 21, 2022 (CN) 202230698382.5
